CLAIM

The ornamental design for a modular radar device, as shown and described.

DESCRIPTION

FIG. 1 is a perspective view of a modular radar device;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left view thereof.

Objects shown in broken lines depict portions of the modular radar device that form no part of the claimed design.
